UNITED STATES PATENT OFFICE

169,747

COMBINED ELECTRIC KETTLE AND STAND

Lawrence George Hawkins, London, England

Application January 26, 1953, Serial No. 23,304
In Great Britain July 30, 1952

Term of patent 14 years

(Cl. D81—10)

To all whom it may concern:

Be it known that I, Lawrence George Hawkins, a British subject, residing in London, England, have invented a new, original, and ornamental Design for a Combined Electric Kettle and Stand, of which the following is a specification, reference being had to the accompanying drawings, forming part thereof.

Fig. 1 is a side view;
Fig. 2 is a plan view;
Fig. 3 is an end view;
Fig. 4 is a perspective view from one side and

above of a combined electric kettle and stand, showing my new design.

I claim:

The ornamental design for a combined electric kettle and stand, as shown.

LAWRENCE GEORGE HAWKINS.
